UNITED STATES PATENT OFFICE.

EARL E. EICKMEYER, OF DAYTON, OHIO, ASSIGNOR TO THE DAYTON PUMP & MANUFACTURING COMPANY, OF DAYTON, OHIO, A CORPORATION OF OHIO.

DESIGN FOR A GASOLINE-PUMP CASING.

Application filed January 20, 1927. Serial No. 20,446. Term of patent 7 years.

To all whom it may concern:

Be it known that I, EARL E. EICKMEYER, a citizen of the United States, residing at Dayton, in the county of Montgomery and State of Ohio, have invented a new and ornamental Design for a Gasoline-Pump Casing, of which the following is a specification, reference being had to the accompanying drawings, forming a part thereof.

In the accompanying drawings:

Figure 1 is a side elevation of a pump showing my new design; and

Figure 2 is a section on the line 2—2 of Fig. 1 and looking in the direction of the arrows.

I claim:

The ornamental design for a gasoline pump casing as shown.

EARL E. EICKMEYER.
